UNITED STATES PATENT OFFICE

FOSTER K. SOLLIDAY AND CORNEILIUS DE RIDDER, OF GRAND RAPIDS, MICHIGAN,
ASSIGNORS TO NATIONAL BRASS COMPANY, OF GRAND RAPIDS, MICHIGAN, A COR-
PORATION OF MICHIGAN

RIGHT AND LEFT HAND LATCH

Application filed January 19, 1931. Serial No. 509,576.

This invention pertains or relates to latch-
ing mechanisms and is more particularly con-
cerned with the construction of a latch which
may be used on either side of a door. In
5 other words, the latch is either right-hand
or left-hand.

One of the main features of this invention
lies in our novel latch bolt together with its
mounting means whereby it may be slid axi-
ally thus permitting it to extend on either
10 side of the handle member in which it is
mounted thus making it capable of acting or
serving on either side thereof, thus, the dealer
or jobber is not compelled to keep two types of
15 latches in stock but instead may handle only
the herein described type, the same being
capable of functioning regardless of the type
of door to which it is applied.

Another feature of our invention is to con-
20 struct a latch which is of extremely simple
construction and which may be properly
manufactured. One of the several ways in
which the cost of manufacture is lessened is
25 by the elimination of any extra parts. For
instance, the spring member not only serves
its usual function but it also prevents the
latching bolt from endwise movement as will
later be set forth.

Briefly described our invention consists of
30 a latch housing having a handle member piv-
otally mounted therein, a latch bolt having
several grooves therein, and a spring coiled
about the pivot between the handle member
and the latch member, said spring having
35 one of its ends received in the chosen one of
the grooves in the latch bolt whereby the latch
bolt is prevented from endwise movement.

Other objects, advantages and meritorious
40 qualities reside in the special construction,
combination and arrangement of the various
elements forming the invention as more fully
hereinafter described and claimed, reference
45 being had to the accompanying drawing
forming part hereof, wherein:

Fig. 1 is a front view of our invention as
applied to a cupboard.

Fig. 2 is a view through the jamb showing
the keeper member.

Fig. 3 is a view in cross section taken 50
through the swinging door.

Fig. 4 is a view taken along the line 4—4 of
Fig. 5.

Fig. 5 is a view taken along the line 5—5
of Fig. 3.

Fig. 6 is a view similar to Fig. 5 but show-
ing the latch bolt in its opposite position.

Fig. 7 is a view in cross section taken
through a modification of my device.

Fig. 8 is a view taken along the line 8—8 of 60
Fig. 7.

Fig. 9 is a view similar to Fig. 8 but show-
ing the latch bolt reversed.

Fig. 10 is a side view of my double keeper
member, and, 65

Fig. 11 is a front view of another modifica-
tion.

Similar numerals refer to similar parts
throughout the several views.

Referring particularly to Figs. 1-6, inclu-
sive, 10 indicates the swinging door of a
cupboard having a jamb 11, the jamb 11 hav-
ing a keeper 12 fastened thereto by means of
bolts 13. The keeper is preferably formed
of a single piece of strap metal, such as iron,
75 plated as desired and having the usual cam
surface 14 against which the latch bolt 15
rides to the closing of the door 10.

The door 10 has the flange or base 16 of
the latch housing 17 held thereto by means
of screws 18. The latch housing 17 has de-
pending sides which serve to mount the pivot
pin 21 which extends therethrough and which
may be riveted over at its ends as clearly 85
shown in Figs. 5 and 6.

A handle member 23 has spaced apart lips
24 extending inwardly between the depend-
ing sides of the latch housing 17 and is pivot-
ed upon the pivot pin 21. The front por- 90

tion of these lips slidably carry the latching bolt 15.

A coiled spring 25 is wound about the pivot pin 21 and one end thereof extends upwardly against the housing 17. See Fig. 4. The latch bolt 15 has circumferential grooves 26 and 27, and the other end of the coiled spring rides in the chosen one of these grooves.

10 For instance, if the latch bolt is to be used as illustrated in Fig. 1, the lower end of the spring rides in a groove 27 and prevents endwise movement of the latch bolt whereas if the latch is used with a reversely hung door 15 the lower end of the spring is shifted to the groove 26. This is accomplished by pulling downwardly upon the lower end of the spring and merely shifting the latch bolt as desired. The dotted line showing of Fig. 1 illustrates 20 this new position. A small lug 29, see Fig. 4, is provided on the lip 24 of the handle member adjacent the lower end of the spring, thus preventing release of the spring in case the latch bolt should be removed.

25 Figs. 7, 8 and 9 show a modified form of our invention which consists of a latch housing 40 having the handle member 41 pivotally mounted therein by means of the pivot 42, said pivot serving also to support the coil spring 43, one end of this spring resting against the housing 40 and the other end being clamped to the handle 41 as indicated at 44. The latch bolt 45 consists of an enlarged portion 46 which is adapted to be bolted 35 against either one of the inner lips of the handle 41, the screw 47 threading into a smaller portion 48 of the latch bolt to accomplish this result. See Fig. 8.

Fig. 9 illustrates the latch bolt 45 when it 40 is reversed.

Fig. 10 illustrates a keeper member 50 which is formed with a recess 51 relatively close to the jamb member 11 and another recess 52 which is farther away, the former being 45 adapted to receive the latch bolt 53 when the latch is used with an ordinary swing door construction and the latter recess being used when the door is offset relative to the jamb member.

50 Fig. 11 illustrates a modification which has a latch housing member 55, a handle member 56 mounted therein and a relatively long latch bar 57 being of sufficient length to operate either right-handedly or left-handedly.

55 Having thus revealed this invention, we claim as new and desire to secure the following combinations and elements or equivalents thereof, by Letters Patent of the United States.

60 We claim:

1. A latch device of the class described comprising a housing having depending sides, a handle member, a pivot extending through the depending sides and the handle 65 member to mount the same, a latch bolt slid-

ably mounted in the handle member, said latch bolt having several circumferential grooves therein, a coiled spring located about the said pivot and having one end bearing against the housing and the other end resting in a chosen groove, said last mentioned end extending beyond the groove whereby it may be grasped readily when desired.

2. A latch device as set forth in claim 1, but further characterized by the fact that the handle means has a projection extending therefrom, said projection being adapted to engage the last mentioned end of the spring between the latch bolt and the pivot of the handle.

3. A latch of the character set forth comprising a housing member, a handle, means for pivoting the handle onto the housing, a latch bolt slidably mounted in the handle in parallelism to the axis of the handle, said latch bolt having a plurality of notches therein, and means mounted on the handle and coacting with one of the notches to prevent axial movement of the latch bolt.

4. A latch as set forth in claim 3 in which the last mentioned means consists of a spring, one end of said spring pushing against the interior of the housing and the other end resting in one of the aforesaid notches whereby longitudinal movement of the latch bolt is prevented.

5. A right and left hand latch comprising a base, a housing rigid therewith, a handle member pivotally mounted on the housing, a latch bolt and means to adjustably mount the latch bolt on the handle member whereby it extends beyond the base on either side thereof.

6. In a latching device of the character described a housing member, a handle member pivoted thereto, a latch bolt slidably mounted in said handle member and means to hold the latch bolt in either of two of its several sliding positions.

7. In a latching mechanism of the type described a housing member, a handle member, means for pivoting the handle member upon the housing member, a latch bolt slidably mounted in said handle member and means to clamp the latch bolt against axial movement, said means being mounted upon the handle member.

8. A latching structure of the character described consisting of a housing, a handle member pivoted therein, a latch bolt mounted in the handle member, and spring means mounted upon the handle member, spring means interposed between the housing and the latch bolt whereby the handle tends towards rotation and whereby the latch bolt is held from axial movement.

9. An article of the class described comprising a supporting housing, a handle pivoted therein, a latch bolt slidably mounted

in said handle, and spring means mounted between the housing and the latch bolt whereby the latch bolt is held in its chosen position and whereby the handle member is flexibly held with relation to the housing.

5 10. A latch device comprising a housing member, a handle pivotally mounted therein, a latch bolt and means to movably mount the latch bolt so as to extend from either side of the handle whereby the latch device is either right hand or left hand as desired.

10 15 In testimony whereof we affix our signatures.
